WORK CLAMP FOR SEWING MACHINES

Alfred R. Wood, Bridgeport, Conn., assignor to
The Singer Manufacturing Company, Elizabeth,
N. J., a corporation of New Jersey

Application May 23, 1945, Serial No. 595,269

17 Claims. (Cl. 112—114)

1

This invention relates to sewing machines, more particularly of the type having stitch-forming mechanism and a work-clamp with means for relatively moving them to sew a predetermined group of stitches; the stitch-forming mechanism coming to rest automatically after the predetermined group of stitches has been sewn in the work. Machines of this type are commonly used for tacking and barring, buttonholing and other operations.

Machines of the type in question have been heretofore provided with a work-clamp adapted to cooperate with the sewing machine stitching and feeding mechanism for the purpose of attaching labels to articles. When attaching labels to blankets and similar soft or spongy articles, the work-clamp sinks into the soft or spongy material to a depth sufficient to cause the margin of the label to curl or incline upwardly. When the free label-edge is thus inclined, it lies along a vertical wall of the clamp and is out of the needle path, with the result that the needle frequently fails to stitch the edge of the label to the article.

It is, therefore, an object of the present invention to provide an improved work-clamp which is adapted to press a label or like article, against a soft or spongy sheet of material in a manner such that the area of the article which is to receive the stitches lies flatwise against the sheet.

With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

In the accompanying drawings

Fig. 1 is a top plan view of a portion of a sewing machine provided with the present improvement.

Fig. 2 is a right side longitudinal elevation, partly in vertical section of portions of the sewing machine and work-clamp; the section being taken substantially along line 2—2 of Fig. 1.

Fig. 3 is a bottom view, partly in section, of a portion of the work-clamp.

Fig. 4 represents a vertical section of the usual form of work-clamp which does not embody the present invention. This view would normally be taken substantially along line 5—5 of Fig. 1, if the work-clamp shown therein was of this type.

Fig. 5 represents a vertical section of the pres-

ent work-clamp taken substantially along line 5—5 of Fig. 1.

The invention, as illustrated in the accompanying drawings, is embodied in a sewing machine of the straight buttonhole type which is disclosed in U. S. Patent No. 885,810, April 21, 1908, E. B. Allen.

As partly shown in Figs. 1 and 2, the present machine comprises a bed 1 in which is journaled a rock-shaft 2 driven by mechanism not herein shown. Upon one end of this shaft is mounted the usual shuttle-driver 3 which actuates the shuttle 4 carried in the race 5 which is in turn mounted upon the bed 1. The machine has the usual endwise reciprocatory and laterally vibratory eye-pointed needle 6 carried and actuated by mechanism not illustrated. The shuttle 4 cooperates with the needle 6 in forming lockstitches in a manner well-known.

The work-clamp, except as hereinafter specifically described, is constructed substantially in accordance with the disclosure in U. S. Patent No. 1,489,295, April 8, 1924; A. R. Wood. The bed 1 of the machine has cut therein guideways 7, 7 for the cross-slide-plate 8 which, in the present machine, is fixed against movement in the guideways 7, 7 by shoulder-screws 9. The present cross-slide-plate 8 has no connection with the usual feed-wheel 10, as it has no movement in the bed 1 during the cycle of operations.

Mounted, as usual, on the cross-slide-plate 8 is the stationary throat-plate or work-supporting plate 11 with the needle aperture 12.

Mounted in guideways 13, 13, in the cross-slide-plate 8 is the longitudinal slide-frame or base-plate 14 of the work-clamp. The base-plate 14 has imparted to it, during a sewing period, step-by-step travelling movements lengthwise of the bed 1, by the usual link 15 and lever-connection 16 with the usual feed-cam groove 17 in the feed-wheel 10. The base-plate 14 carries a lateral extension 18 on which is pivoted, in the usual manner, the upper clamp-arm 19 upon which presses the usual clamp-closing spring-biasing unit 20. The clamp-arm 19 includes two spaced forward extensions 21, 22, to the ends of which is secured by screws 23, 24, the clamp-foot frame 25 having the rectangular stitch-receiving aperture, defined by the walls 26, and the serrated fabric-clamping ribs 27 at the sides of the aperture. The serrated ribs 27 act as work-gripping surfaces so as to clamp the work against the smooth top surface portion 28 of the work-supporting throat-plate 11. The top portion 28 of the throat-plate 11 is smooth throughout its

entire length and the work slides along this plate while under the pressure of the clamp-foot 25 during a sewing period.

Secured to the upper clamp-arm 19 by screws 29 is a tail-piece 30 which is adapted to be actuated to raise the clamp in the usual manner, as disclosed in U. S. Patent No. 1,966,432, July 17, 1934, E. B. Allen et al.

The clamp-foot frame 25 is fitted with the usual pivoted needle-thread cutter and nipper blades 31 and 32 which are operated by mechanism constructed substantially in accordance with the disclosure of U. S. Patent No. 1,839,823, January 5, 1932, A. R. Wood. The thread-cutter operating mechanism is not described herein as it forms no part of the present invention.

According to the present invention, the vertical walls 26, which define the elongated opening in the clamp, are provided with longitudinal grooves 33, 33 in which is slidably disposed the head 34 formed at the front end of an elongated flat label presser-blade 34. The blade head 34 is provided with a needle-clearance slot 35, the blade 34 having a supporting shank 36 and sight or label alining holes 37. The shank 36 of the blade is pivotally secured by a screw 38 to an ear 39 of a stationary bracket-member fixed to the bed 4. The label presser-blade, through the medium of its pivotal connection, may be raised and lowered with the clamp and, furthermore, this connection will prevent any endwise movement of the presser-blade 34 relative to the needle 6 during the work-shifting movement of the work-clamp. The presser-blade 34 is provided in its bottom portion with a longitudinal groove 40 for the purpose of providing relief directly above that portion of the work which is adapted to receive the stitches. This relief is effective to reduce to a minimum the opposition to the feeding of the work by the work-clamp relatively to the stationary blade 34.

Secured to the base-plate 14, by means of the screws 41 and 42 is a work-supporting apron 43 which is shifted back and forth relative to the needle 6 in response to the action of the feed-wheel 10. In order to prevent the work from dropping down and being caught between the forward portion of the apron and the work-supporting plate 11, there is secured to the under side of the apron 43 a tongue 44 of which the free end portion is slidably supported on the throat-plate 11.

With particular reference to Fig. 5, it may be seen that with the present construction, when the clamp 25 is lowered to hold the label 45 on the spongy material 46, the blade 34 and its head 34 engage the free marginal portion 47 of the label 45 and hold it down against the material 46. As the clamp 25 feeds the material 46 and label 45 relative to the needle 6, in the usual manner, the presser-blade 34 remains stationary and the edge of the label slides under the presser-blade 34 and is presented in a substantially flat position, as shown in Fig. 5, to the stitch-forming mechanism.

In the sewing machine chosen to illustrate the present improvement, the presser-blade 34 maintains the marginal portion of the label 45 in a flattened position such that the vibratory needle successively steps over the edge of the label and thereby effectively overstitches and conceals the edge of the label. This is desirable because a finished product of high quality can be produced by using a less expensive cut edge label, instead of the more expensive selvage edge label.

Fig. 4 illustrates the usual type of clamp without the present improvement. It may be readily

understood that due to the spongy character of the material 46, the clamp 25 will sink into the same to the extent that the marginal portion 47 of the label 45 will project upwardly and possibly out of the vertical path of the needle 6. Clearly, the present invention, as best shown in Fig. 5, overcomes the shortcomings inherent in the prior type of work-clamp.

Having thus set forth the nature of the invention, what I claim herein is:

1. In a sewing machine, in combination, stitch-forming mechanism including a reciprocatory needle, a work-clamp provided with a needle-clearance opening, means for relatively moving said needle and work-clamp lengthwise of the work-clamp opening, a work-presser disposed within said opening of the work-clamp and provided with a needle-clearance slot, and supporting means providing for relative movement of said work-clamp and work-presser lengthwise of said needle-clearance opening of the work-clamp.

2. In a sewing machine, in combination, stitch-forming mechanism including a reciprocatory needle, a work-clamp provided with a needle-clearance opening, means for relatively moving said needle and work-clamp lengthwise of the work-clamp opening, a work-presser comprising a blade disposed lengthwise within the work-clamp opening and provided at one end with a widened head, said head extending entirely across said work-clamp opening in the region of the path of reciprocation of said needle, and supporting means providing for relative movement of said work-clamp and work-presser lengthwise of the work-clamp opening.

3. In a sewing machine, in combination, stitch-forming mechanism including a reciprocatory needle, a work-clamp provided with a needle-clearance opening, means for relatively moving said needle and work-clamp lengthwise of the work-clamp opening, a work-presser comprising a blade disposed lengthwise within the work-clamp opening and provided with a widened head in the region of the path of reciprocation of said needle, said head being slidably supported by said work-clamp at opposite sides of said work-clamp opening, and means for imparting relative movement to said work-clamp and work-presser lengthwise of the work-clamp opening, upon relative movement of said needle and work-clamp in the same direction.

4. In a sewing machine, in combination, stitch-forming mechanism including a reciprocatory needle, a work-clamp provided with a needle-clearance opening, means for relatively moving said needle and work-clamp lengthwise of the work-clamp opening, a work-presser comprising a blade disposed lengthwise within the work-clamp opening, and provided at one end with a head having a needle-clearance slot, said blade having a plurality of sight apertures and said head being slidably supported by said work-clamp at opposite sides of said work-clamp opening, and means for imparting relative movement to said work-clamp and work-presser lengthwise of said work-clamp opening in timed relation with the relative movement of said needle and work-clamp in the same direction.

5. In a sewing machine, in combination, stitch-forming mechanism including a reciprocatory needle, a travelling work-clamp provided with a needle-clearance opening, means for shifting said work-clamp lengthwise of the work-clamp opening, a work-presser having a needle-slot and slidably supported by said work-clamp at op-

posite sides of said work-clamp opening, and means anchoring said work-presser against movement with said work-clamp.

6. In a sewing machine, in combination, stitch-forming mechanism including a reciprocatory needle, a work-clamp provided with a needle-clearance opening, means for relatively moving said needle and work-clamp lengthwise of the work-clamp opening, a work-presser disposed within said opening and having a needle-clearance slot, said work-presser being provided at the work-side thereof with a work-clearance groove extending lengthwise of the work-clamp opening, and supporting means providing for relative movement of work-clamp and work-presser lengthwise of said work-clamp opening.

7. In a sewing machine having a bed carrying a work-supporting plate formed with a needle aperture, a clamp-foot opposed to said work-supporting plate, said foot having a rectangular stitch-receiving aperture and means at the sides of said aperture adapted for cooperation with said plate to grip the work, a lever supporting said foot, clamp-closing means applied to said lever, an auxiliary clamp member containing a needle aperture in one end portion thereof, said auxiliary clamp being slidably received lengthwise within said stitch-receiving aperture, means to connect that end of the auxiliary clamp remote from the needle aperture with said bed, and feeding mechanism to move said foot and the work thereunder relative to said work-supporting plate and said auxiliary clamp for the reception of stitches.

8. A work-clamp comprising a stationary bed, a work-supporting plate carried by said bed, a clamp-foot having a work-gripping surface opposed to said plate, an arm carrying said foot, an auxiliary presser-member having a needle aperture therein, one end of said auxiliary presser being pivotally secured to said bed and having the other end thereof carried by said clamp-foot, clamp-closing means applied to said arm for pressing the clamp-foot and auxiliary presser upon the work resting upon said work-supporting plate, and feeding mechanism to move said clamp-foot and the work thereunder relatively to said work-supporting plate and said auxiliary presser.

9. A sewing machine work-clamp comprising a stationary bed, a work-supporting plate carried by said bed, a clamp-foot opposed to said work-supporting plate, said foot having a rectangular stitch-receiving aperture, means at the sides of said aperture to grip work resting upon said plate, auxiliary presser means carried by said foot and positioned within the aperture thereof, a lever supporting said foot, clamp-closing means connected to said lever for pressing the foot and said auxiliary presser upon the work resting upon said plate, means pivotally connecting said auxiliary presser to said bed, and feeding mechanism to move said foot and the work thereunder relatively to said work-supporting plate and said auxiliary presser means.

10. A work-clamp for sewing machines having a stationary bed with a work-supporting plate carried thereby, said clamp comprising a foot portion opposed to said work-supporting plate and having an elongated stitch-receiving aperture, work-clamping portions at the under face of said foot at the sides of said aperture, an auxiliary presser member slidably mounted lengthwise within said aperture, means connect-

ing said auxiliary presser member with said bed, and means to feed said foot and the work thereunder relatively to said work-supporting plate and said auxiliary presser means in the direction of the stitch-receiving aperture elongation.

11. A work-clamp for sewing machines having a stationary bed with a work-supporting plate carried thereby, said clamp comprising, a foot portion opposed to said work-supporting plate and having an elongated stitch-receiving aperture, work-clamping portions at the under face of said foot at the sides of said aperture, an auxiliary clamp member having a needle aperture in one end portion thereof which is slidably mounted lengthwise within said stitch-receiving aperture, means connecting that end of said auxiliary clamp remote from the needle aperture with said bed, and means to feed said foot and the work thereunder relatively to said work-supporting plate and said auxiliary clamp in the direction of the stitch-receiving aperture elongation.

12. The combination with a sewing machine having a bed, and a smooth surfaced stationary work-supporting plate mounted upon said bed and having a needle aperture therein, of a work-clamp having a lower plate slidable longitudinally of but fixed laterally with relation to said work-supporting plate, a clamp-lever carried on said lower plate, a clamp-foot carried by said lever and having a rectangular stitch-receiving opening and work-gripping portions at the sides of said opening clampingly opposed to said work-supporting plate, an auxiliary clamp member having one end portion thereof slidably received longitudinally within said stitch-receiving opening, means to pivotally connect the other end portion of said auxiliary clamp to said bed, and feeding means to move said work-clamp longitudinally of and relative to said work-supporting plate and said auxiliary clamp.

13. The combination with a sewing machine having a bed, a smooth surfaced stationary work-supporting plate mounted upon said bed, and stitching mechanism including a needle adapted to perform a group of barring stitches, of a work-clamp having a lower plate slidable longitudinally of but fixed laterally with relation to said work-supporting plate, a clamp-lever carried on said lower plate, a clamp-foot carried by said lever and having a rectangular stitch-receiving opening, work-gripping portions at the sides of said opening clampingly opposed to said work-supporting plate, an auxiliary clamp member having a needle aperture in an end portion thereof which is slidably mounted within a pair of parallel grooves, each of said grooves being provided longitudinally of and adjacent the bottom edge of one of the opposite side walls of said stitch-receiving aperture, means connecting that end of said auxiliary clamp remote from the needle aperture with said bed, and feeding means to move said work-clamp longitudinally of and relative to said work-supporting plate and said auxiliary clamp.

14. In a sewing machine having a bed, a stationary work-supporting plate mounted upon said bed, and stitching mechanism including a needle, a two-part work-clamp comprising one member having a rectangular stitch-receiving aperture, a second member slidably mounted lengthwise within said aperture, work-gripping means provided at the bottom face of one of said two members, means to press said two members toward said work-support, means to feed one of said members and the work beneath the same

past said stitching mechanism, and means to hold the other member fixed relative to said work-supporting plate.

15. In a sewing machine having a bed, a stationary work-supporting plate mounted upon said bed, and stitching mechanism including a needle adapted to perform a group of barring stitches, a two-part work-clamp comprising one member having a stitch-receiving aperture, a second member having a needle aperture therein, said second member being directly opposed to said work-supporting plate and being positioned between the aperture-defining side-walls of said first member, work-gripping means provided at the bottom face of one of said two members, means to press each of said members toward said bed, means to raise both members simultaneously off the work, means to feed one of said members and the work beneath the same past said stitching mechanism, and means to hold the other member fixed relative to said work-supporting plate.

16. In a sewing machine, in combination, stitch-forming mechanism including a reciprocating needle, a work-clamp provided with a needle-clearance opening, means for relatively

5 moving said needle and work-clamp lengthwise of the work-clamp opening, and a work-presser slidably supported by said work-clamp at opposite sides of said work-clamp opening for relative movement of the work-clamp and work-presser lengthwise of said opening, said work-presser extending across said work-clamp opening in the region of the path of reciprocation of said needle.

17. In a sewing machine, in combination, stitch-forming mechanism including a reciprocating needle, a work-clamp provided with a needle-clearance opening, means for relatively moving said needle and work-clamp lengthwise of the work-clamp opening, a work-presser disposed within said opening of the work-clamp and having a portion thereof extending entirely across said opening in the region of the path of reciprocation of said needle, and supporting means providing for relative movement of said work-clamp and work-presser lengthwise of said needle-clearance opening and for preventing relative movement of said work-clamp and work-presser in a direction normal to the plane of the work.

25 ALFRED R. WOOD.
